REFERENCE VOLTAGE GENERATOR AND REGULATOR

BACKGROUND

In the present technology, the integrated circuit is being utilized in more and more applications. There are several types of integrated circuitry known. One popular type of integrated circuit technology uses the so called COS/MOS (i.e., Complementary-Metal-Oxide-Semiconductor) integration process. This type of process or technology permits many circuits to be produced utilizing the standard MOS type advantages as well as the advantages which are provided by using the COS/MOS techniques. These advantages, such as low power requirements, high packing density and low power-delay product, are well known in the art.

When producing circuits or systems utilizing COS/MOS techniques, it frequently becomes necessary to include a means for providing regulation of one or more of the voltages which are utilized or generated by the circuit. As one approach to providing the regulation, it is frequently desirable to provide a reference voltage to which the circuit may be referenced. Moreover, it is desirable that the reference voltage be substantially independent of any fluctuations in the supply voltage or, alternatively, due to temperature changes or the like. Furthermore, it is important that the regulator circuit should not be a power drain on the overall system. Another desirability is to be able to produce the voltage generator and regulator using standard COS/MOS processing techniques whereby the circuit can be integrated along with the associated COS/MOS circuitry. The use of a COS/MOS regulator, on the same chip as the associated COS/MOS circuitry, permits the full utilization of the low power requirement advantage of COS/MOS circuitry.

SUMMARY OF THE INVENTION

A voltage generator and regulator circuit is provided wherein a first portion of the circuit operates upon standard supply voltages to produce or generate a reference voltage which is substantially independent of variations in supply voltage or temperature. The output voltage from the voltage generator is supplied to a regulator circuit which produces an output voltage which is regulated as a function of the reference voltage. Thus, the output from the regulator circuit is a regulated voltage which is controlled by a relatively accurate reference voltage.

BRIEF DESCRIPTION OF THE DRAWING

The single FIG. is a schematic diagram of one embodiment of the instant invention.

DESCRIPTION OF THE PREFERRED EMBODIMENT

In the single figure, the reference voltage generator circuit portion shown generally at 50 is connected to the regulator circuit portion, shown generally at 51. Each of the circuit portions includes semiconductor devices of the well known MOS field effect transistor type. Each of these semiconductors includes a conduction path between the drain and source electrodes and a gate electrode for controlling conduction through the conduction path. In this embodiment, P-type MOS devices are rendered conductive when the gate electrode

is negative relative to the source electrode. Conversely, N-type MOS devices are rendered conductive when the gate electrode is positive relative to the source electrode.

5 In the reference voltage generator, the input voltages are supplied at terminals 10 and 11, respectively. Input terminal 10 may represent ground potential or any suitable reference source (V_{DD}) while terminal 11 is connected to source V_{SS} , the voltage to be regulated by circuit 51. The voltage V_{DD} is positive relative to V_{SS} . A P-type semiconductor device P1 has the source electrode (S) and the substrate thereof connected to terminal 10. The drain electrode (D) of device P1 is connected to the cathode of Zener diode Z2. The anode of 15 Zener diode Z2 is connected to terminal 11 along with the gate electrode (G) of P-type semiconductor device P2. The drain electrode (D) of device P2 is connected to the cathode of Zener diode Z2. The source electrode (S) and substrate of device P2 are connected to terminal 10. The cathode of Zener diode Z2 is also connected to the gate electrode (G) of N-type semiconductor device N1. The source electrode (S) and substrate of device N1 are connected to terminal 11. The drain electrode (D) of device N1 is connected to the 20 anode of Zener diode Z1. The cathode of Zener diode Z1 is connected to terminal 10. The anode of Zener diode Z1 is also connected to the gate electrode of device P1 and to the regulator circuit portion along line 13. The cathode of Zener diode Z2 is connected to the regulator circuit portion along line 12.

In the series voltage regulator circuit portion 51, the source electrode (S) and the substrate of semiconductor device P3 are connected to source V_{DD} at terminal 10. The gate electrode (G) of device P3 and the gate electrode (G) of device P4 are connected to the reference input source supplied at line 13 from voltage generator 50. The drain electrode (D) of device P3 is connected to the source electrodes of devices P4 and P5. The drain electrode (D) of device P5 is connected to terminal 11 and source V_{SS} . The drain electrode (D) of device P4 is connected to the drain electrode (D) of device N2. The source electrode (S) and the substrate of device N2 are each connected to terminal 11. The gate electrode (G) of device N2 is connected to line 12 which, in this embodiment, is a source of a constant voltage, relative to source V_{SS} , supplied by voltage generator 50. In an alternative embodiment, line 12 may be connected to source V_{DD} at terminal 10. In the alternative embodiment, some control over the impedance of device N2 and, thus over the circuit, may be lost in the case of widely fluctuating V_{DD} .

The drain electrode of device P5 is also connected to terminal 11 along with the source electrode (S) and the substrate of device N3. The drain electrode (D) of device N3 and the gate electrode (G) of device P5 are connected to output terminal 14 at which a voltage V_{CC} is regulated by the circuit 51. The gate electrode (G) of device N3 is connected to the common junction of the drain electrodes of devices P4 and N2. The substrates of devices P4 and P5 are also connected to V_{DD} .

Typically, device P3 is of medium impedance (i.e., higher than P4, P5 and N3 but lower than N2) and is normally turned on whereby there is a substantially constant source-drain current therethrough. Also, device N3 is the regulating device in the circuit and is of relatively low impedance (i.e., of approximately the same impedance as devices P4 and P5). With the cir-

cuit configuration shown, the drain-source voltage of device N2 is the gate-source voltage of device N3.

In operation, an essentially constant voltage is supplied to the gate electrode of device N1 by Zener diode Z2. Consequently, when saturation of N1 is reached, device N1 operates as a constant current source and supplies current to Zener diode Z1. Conversely, the current through Zener diode Z2 is supplied by device P1 which also operates as a constant current source after saturation is achieved. That is, an essentially constant voltage is applied to the gate of device P1 by Zener diode Z1, which voltage biases device P1 in saturation. Thus, the current through Zener diode Z2 is supplied by device P1 while the current through Zener diode Z1 is supplied by device N1. The circuit comprising devices N1 and P1 and Zener diodes Z1 and Z2 tends to operate as a flip-flop. That is, once the circuit achieves the steady state condition, it latches in this condition and substantially constant voltages relative to V_{ss} and V_{dd} are applied at lines 12 and 13. These voltages are defined as a function of the Zener voltage drop across Zener diodes Z1 and Z2. This type of operation results when the currents supplied to Zener diodes Z1 and Z2 by devices N1 and P1, respectively, are of sufficient magnitude to bias the diodes Z1 and Z2 at points in the constant or Zener voltage portions of their I-V operating characteristics. It is possible for the circuit to latch in the inoperative condition if insufficient current is supplied to the Zener diodes by the devices P1 and N1. This condition will produce insufficient voltage drops across the Zener diodes whereby devices P1 and N1 will remain nonconductive.

Therefore, semiconductor device P2, which is a high impedance device, is provided. Whenever a supply voltage greater than the threshold voltage of device P2 is connected between nodes 10 and 11, semiconductor device P2 is conductive and is designed to supply sufficient current through Zener diode Z2 to produce a voltage of at least the N-threshold across Zener diode Z2 thereby causing device N1 to be rendered conductive. Of course, when device N1 is conductive, device P1 is rendered conductive because the current through N1 produces a voltage drop across Z1 which is greater than the P-threshold for device P1. In fact, in some applications where regulation is not so critical, device P1 may be eliminated whereby device P2 maintains the turn-on current for Zener diode Z2, as suggested supra. In this alternative configuration the control of the voltage on line 12 is somewhat reduced. However, the performance of both circuits is satisfactory and very similar.

The reference voltages produced by voltage generator 50 are supplied to regulator 51 along lines 12 and 13. In particular, the voltage on line 12 is a constant control voltage which controls the impedance of device N2 which is a high impedance device relative to devices P3, P4, P5 and N3. Because the gate electrode is at one fixed value of potential V_{12} and the source electrode at another fixed value of potential V_{ss} , device N2 operates as a constant current means. The voltage on line 13 is the reference voltage upon which the regulator operates to produce the regulated voltage V_{cc} .

The transistors P4, P5 receiving the current supplied by source P3 of the regulator circuit operate as a differential amplifier. They compare the voltage V_{13} on line 13 with the output voltage V_{cc} at terminal 14 in the manner discussed in detail below.

In typical operation, if the output voltage V_{cc} measured between terminals 10 and 14 is larger (i.e., less positive or more negative) than the reference voltage measured between terminals 10 and 13, low impedance device P5 is relatively more conductive than low impedance device P4 whereby substantially all of the current from device P3 is passed through device P5. Conversely, device P4 is relatively nonconductive whereby its impedance is much higher than that of N2. 10 Consequently, the voltage drop across device N2 drops to near zero wherein device N3 is rendered nonconductive. When device N3 is nonconductive, the output voltage at terminal 14 is reduced (becomes less negative or more positive) inasmuch as current is not supplied to terminal 14 from the source represented by terminal 13.

Conversely, if the voltage V_{cc} at terminal 14 is smaller (i.e., less negative) than the reference voltage on line 13, device P4 is rendered conductive and device 20 P5 is rendered nonconductive. Consequently, current flows through the series connected conduction paths of devices P4 and N2 to source 11. As a result of the current through devices P4 and N2, the voltage drop across device N2 increases because device N2 is of 25 much higher impedance than P4 whereby the voltage applied to the gate electrode of device N3 becomes more positive (relative to V_{ss}). In response to the voltage condition at the gate electrode thereof, device N3 is rendered conductive and connects terminal 11 to terminal 14. Consequently, the output voltage at terminal 14 increases (becomes more negative or less positive) as a result of the current supplied via device N3.

When the output voltage at terminal 14 is equal to the reference voltage on line 13, devices P4 and P5 are 35 both conductive wherein the current from source P3 is split between devices P4 and P5. The current split is effective to stabilize the operation of the circuit. In this condition, device N3 is just barely conductive.

Furthermore, the circuit loop includes only one inversion, i.e., if the output voltage at terminal 14 becomes more positive, the voltage at the gate electrode of device N3 becomes more positive and this causes the voltage at terminal 14 to become more negative. This is the only inversion in circuit 51. With only one inversion, oscillation (or hunting) of the output voltage V_{cc} is possible only for the case of extremely high impedance loads. That is, with high impedance loads, even small load currents produce large voltage swings across the load and, thus, at terminal 14. These large voltage swings can cause oscillation inasmuch as the circuit cannot follow precisely enough and limit the swing. However, the loads for this circuit typically will not be of the magnitude to permit this type of operation. Conversely, small loads (e.g., load currents in the low microampere range) cause the circuit to be extremely stable. Of course, in typical applications of the circuit in integrated circuit form, the load currents will be quite small. However, some type of load, even though small, should preferably be provided in order to assure that 55 the voltage at terminal 14 can be returned towards the V_{dd} level. That is, zero load produces an operation wherein the voltage level at terminal 14 can be reduced to below the reference voltage level (V_R) at line 13 but cannot be increased from a voltage level below the reference level.

The circuit shown is especially adapted to integrated circuit fabrication especially of the COS/MOS variety.

For example, referring to voltage generator 50, it is known that in the normal COS/MOS fabrication process, P- and N-channel MOS enhancement field effect transistors on a monolithic substrate include a P+ and an N+ diffusion for the drain and source electrodes of the P and N units, respectively. If the N+ diffusion is diffused into a P+ diffusion, a P+ N+ junction is obtained. This type of junction as a Zener characteristic. Moreover, the Zener voltage produced by this junction has a positive temperature coefficient. Inasmuch as semiconductor devices N1, P1 and P2 of voltage generator 50 have negative temperature coefficients, the circuit can be designed to produce a substantially temperature independent voltage source. This circuit together with regulator circuit 51 can be fabricated using the normal COS/MOS techniques whereby a sophisticated power regulator source for a logic system can be integrated on the same monolithic chip of an integrated circuit.

The combined circuits, thus, produce a circuit which regulates a variable load at the output so that a relatively constant voltage substantially equal to a reference voltage is produced. This circuit also has a very small power consumption in comparison to the maximum load.

Thus, there has been described one embodiment of a voltage generator and regulator circuit which has the described advantages. The circuit is described in terms of MOS type integrated circuitry. The specific circuitry shown is illustrative of the invention; however, the scope of the invention is defined by the appended claims.

What is claimed is:

1. In combination, source means having first and second terminals, a plurality of semiconductor devices each having a conduction path and a control electrode for controlling the conduction through said conduction path, first and second semiconductor devices of a first conductivity type having one end of the conduction paths thereof connected together in a common junction, a third semiconductor device of said first conductivity type having the conduction path thereof connected between the common junction at said first and second semiconductor devices and said first terminal of said source means, a fourth semiconductor device of a second conductivity type having the conduction path connected between the conduction path of said first semiconductor device and said second terminal of said source means, an output terminal, a fifth semiconductor device of said second conductivity type having the conduction path thereof connected between said second terminal of said source means and said output terminal, reference source means connected to the control electrodes of said first and third semiconductor devices to establish a conduction level in said first and third semiconductor devices, and control source means connected to the control electrode of said fourth semiconductor device to establish a conduction level therein, the control electrode of said fifth semiconductor device connected to the common connection of said

first and fourth semiconductor device conduction paths to control the conduction of said fifth semiconductor device as a function of the voltage level at said common connection thereby to control the voltage at said output terminal, the control electrode of said second semiconductor device connected to said output terminal to control the relative conduction of said first and second semiconductor devices as a function of the voltage level at said output terminal relative to the voltage supplied by said reference source.

2. The combination recited in claim 1 wherein said semiconductor devices are MOS field effect transistors formed on a common substrate.

3. The combination recited in claim 1 wherein said first, second and fifth semiconductor devices normally exhibit substantially similar impedance values, said fourth semiconductor device exhibits an impedance value which is substantially greater than the impedance value of said first, second and fifth semiconductor devices, and said third semiconductor device exhibits an impedance value between the impedance values of said fourth semiconductor device and said first, second and fifth semiconductor devices.

4. The combination recited in claim 1 including load means connected between said output terminal and said first terminal of said source means.

5. In combination, source means having first and second terminals, a plurality of semiconductor means, each of said semiconductor means having a conduction path with a terminal at each end thereof and a control electrode for controlling the conduction through said conduction path, said semiconductor means being of first or second conductivity type, first semiconductor means of said first conductivity type, second semiconductor means of said second conductivity type, first Zener diode means connected in series with the conduction path of said first semiconductor means, second Zener diode means connected in series with the conduction path of said second semiconductor means,

means connecting said control electrode of said first semiconductor means to a common connection between said second semiconductor means and said second Zener diode means,

means connecting said control electrode of said second semiconductor means to a common connection between said first semiconductor means and to said first Zener diode means,

said first Zener diode means and one terminal of said conduction path of said second semiconductor means connected to said second terminal of said source means,

said second Zener diode means and one terminal of said conduction path of said first semiconductor means connected to said first terminal of said source means,

third and fourth semiconductor means of said first conductivity type having one terminal of the conduction paths thereof connected together in a common junction,

the other terminal of the conduction path of said fourth semiconductor means connected to said second terminal of said source means,

fifth semiconductor means of said first conductivity type having the conduction path thereof connected between the common junction at said third and fourth semiconductor means and said first terminal of said source means,

sixth semiconductor means of said second conductivity type having the conduction path connected between the conduction path of said third semiconductor means and said second terminal of said source means,

an output terminal,

seventh semiconductor means of said second conductivity type having the conduction path thereof connected between said second terminal of said source means and said output terminal,

the control electrodes of said third and fifth semiconductor means connected to said common connection between said second semiconductor means and said second Zener diode means to establish a conduction level in said third and fifth semiconductor means, and

the control electrode of sixth semiconductor means connected to said common connection between said first semiconductor means and said first Zener diode means to establish a conduction level therein,

the control electrode of said seventh semiconductor means connected to the common junction at said third and sixth semiconductor means conduction paths to control the conduction of said seventh conductor means as a function of the voltage level at said common junction thereby to control the voltage at said output terminal,

the control electrode of said fourth semiconductor means connected to said output terminal to control the relative conduction of said third and fourth semiconductor means as a function of the voltage level at said output terminal relative to the voltage supplied to the control electrodes of said third semiconductor means.

6. In a voltage regulating circuit of the type comprising first and second transistors connected in differential amplifier configuration; current source means connected to said differential pair to supply current thereto; means for providing a reference potential to the control electrode of said first transistor; means for connecting the control electrode of said second transistor in circuit with an output terminal the voltage at which is to be regulated; and a series pass transistor connected in series with said output terminal and adapted to regulate the supply of line current to said output terminal as a function of the signal applied to the control electrode of said series pass transistor, the improvement comprising:

a further transistor having its conduction path connected in series circuit with the conduction path of said first transistor and connected to operate as a constant current source, the conduction path of said further transistor exhibiting a relatively high impedance to said first transistor whereby the output signal from said first transistor is applied as a control signal to the control electrode of said series pass transistor.

7. A voltage regulating circuit comprising:

first and second transistors having one end of each of the conduction paths thereof connected together at a common junction;

means for providing a relatively constant current to said common junction;

means for providing a relatively fixed reference potential to the control electrode of said first transistor to bias said first transistor into conduction;

means for connecting a load to the control electrode of said second transistor, the voltage drop across said load being the voltage to be regulated;

feedback means including a third transistor having its control electrode connected in circuit with the other end of the conduction path of said first transistor and further having one end of its conduction path connected in circuit with the control electrode of said second transistor, the conduction path of said third transistor being connected in series with the load for controlling the current level therethrough;

a fourth transistor having its conduction path connected in series with the conduction path of said first transistor; and

means for providing a constant reference potential to the control electrode of said fourth transistor to bias said fourth transistor into conduction, the conduction path of said fourth transistor exhibiting a relatively high impedance to the output signal produced by said first transistor whereby said output signal is directly applied as a control signal to the control electrode of said third transistor.

8. A voltage regulating circuit as recited in claim 7 wherein the impedance of the conduction path of said fourth transistor is substantially greater than the impedance of the conduction paths of said first, second and third transistors for the same value of bias condition, and wherein said first and second transistors are of one conductivity type and said third and fourth transistors are of a second conductivity type.

9. A voltage regulating circuit as recited in claim 8 further comprising:

first and second terminals adapted for connection to a source of potential, said common junction being connected in circuit with said first terminal through said relatively constant current means;

means for connecting the conduction paths of said third and fourth transistors in circuit with said second terminal; and

circuit loading means connected between said first terminal and the control electrode of said second transistor.

10. In combination:

first and second field effect transistors each having a conduction path and a control electrode for controlling the current flow therethrough, and a current source coupled to said paths for supplying current in parallel to said paths;

a circuit point at a reference potential connected to the control electrode of the first transistor;

a second circuit point at which a voltage to be regulated appears, connected to the control electrode of the second transistor, said voltage being a function of the current supplied to said second circuit point;

current sensing means comprising a constant current element connected in series with the conduction path of the first transistor;

a second current source; and

a signal responsive conduction path located between said second current source and said second circuit

point coupled to said current sensing means for regulating the flow of current from said second current source to said second circuit point to thereby regulate the voltage at said second circuit point.

11. The combination as set forth in claim 10 wherein said current sensing means comprises a third field ef-

fect transistor having a conduction path connected in series with that of the first transistor, and having a control electrode connected to a point of fixed reference potential for maintaining the impedance of said path at a given value.
